UNITED STATES PATENT OFFICE.

WILLIAM H. MORGAN AND FRANK A. HANNUM, OF WARE, MASSACHUSETTS.

STOP-MOTION FOR CARDING-MACHINES.

SPECIFICATION forming part of Letters Patent No. 681,563, dated August 27, 1901.

Application filed May 20, 1901. Serial No. 61,132. (No model.)

To all whom it may concern:

Be it known that we, WILLIAM H. MORGAN and FRANK A. HANNUM, citizens of the United States, residing at Ware, in the county of

5 Hampshire and State of Massachusetts, have invented new and useful Improvements in Stop-Motions for Carding-Machines, of which the following is a specification.

Our invention relates to improvements in 10 stop-motion devices; and the object of the same is to produce a device of this character applicable to cotton-carding machinery.

Our device is connected to the calender-rolls and is operated thereby to actuate a 15 lever which throws the doffer out of gear and stops the machine, all of which will be explained in the following specification and illustrated in the accompanying drawings, forming a part thereof, in which—

20 Figure 1 is a perspective of the calender-rolls with our device attached thereto. Fig. 2 is a detail of the catch-plate.

Like numerals of reference designate like parts in both views of the drawings.

25 The numerals 1 and 2 designate calender-rolls, which will be respectively referred to as the "upper" and "lower" rolls. The lower roll 2 has spindles 3, journaled in boxes rigidly mounted on the framework 4. The upper roll 11

30 has spindles 5, mounted in slots 6 and capable of a vertical movement. A yoke 7, having upwardly-extending arms 7^a and a cross-bar 8, is attached to the spindles 5 by means of boxes 9, secured to the ends of the arms 7^a.

35 A lever 10, fulcrumed at 11, is connected intermediate its ends to the cross-bar 8. The outer end of the lever 10 bears a downwardly-extending arm 12, provided with a screw-shank 13 and a bifurcated head 14. The bifurcated head 14 is pivotally attached to an arm 15, integral with a catch member 16, pivoted to an arm 17 on a stud 18, adjustably mounted in a slot 19. The catch member 16 is traversed by two intersecting slots 20, in-

40 closing a V-shaped tongue 21, having a blunt vertex 22. A lever 23, fulcrumed at one end on a standard 24, normally rests on the vertex 22. The lever 23 is connected by means (not shown) to throw the doffer mechanism 45 of the machine out of gear when the said lever is displaced from its position on the ver-

tex 22. By this arrangement any displacement of the yoke would be immediately transmitted to the catch member 15.

When in operation, the catch member is 55 adjusted to hang vertical with the lever 23, resting on the vertex 22, when a normal thickness of cotton is passing through the calender-rolls 1 and 2. If a lesser or greater thickness should attempt to pass through the rolls 60 1 and 2 in consequence of some derangement of the machinery, the roll 1 would be displaced from the normal position, which movement would be communicated to the catch member 15 through the medium of the yoke 65 7, lever 10, and arm 12. The member 15 would be displaced from the vertical, and the lever 23 would slide off of the vertex 22, throw the doffer mechanism out of gear, and stop the machine.

We do not wish to be limited as to details of construction, as these may be modified in many particulars without departing from the spirit of our invention.

It is obvious that our device may be applied to any pair of rolls and the lever 23 used to stop any auxiliary device.

Having thus described our invention, what we claim as new, and wish to secure by Letters Patent, is—

1. In a device of the class described, the combination with a pair of rolls and means for driving said rolls, of a yoke connected to one of said rolls, a lever connected to said yoke, a pivoted catch member having a blunt 85 V-shaped tongue thereon, said member being connected to said lever, a lever normally resting on the vertex of said V and means connected to said lever to be controlled thereby, substantially as described.

2. In a device of the class described, a pivoted catch member provided with a blunt V-shaped tongue, a lever normally resting on the blunt point of said tongue, means connected to said lever to be controlled thereby 95 and means for operating said catch member to displace said lever, substantially as described.

3. In a device of the class described, the combination with a roll mounted to be transversely displaced, a yoke connected to said roll, a pivoted catch member having a V-

shaped tongue thereon, means for connecting said yoke and said catch member, and a stop-motion device having a lever located to be engaged by said tongue, substantially as described.

4. In a device of the class described, the combination with a roll mounted to be displaced transversely, a pivoted catch member having a V-shaped tongue thereon, means for connecting said roll and said catch member, a lever normally supported by said tongue,

and means connected to said lever to be controlled thereby, substantially as described.

In testimony whereof we have hereunto set our hands in presence of two subscribing ¹⁵ witnesses.

WILLIAM H. MORGAN.
FRANK A. HANNUM.
